UNITED STATES PATENT OFFICE

93,948

DESIGN FOR A HEATER CABINET

Eugene L. Snyder, Canton, Ohio

Application October 1, 1934, Serial No. 53,443

Term of patent 7 years

To all whom it may concern:

Be it known that I, EUGENE L. SNYDER, a citizen of the United States, residing at Canton, in the county of Stark and State of Ohio, have invented a new, original, and ornamental Design for Heater Cabinets, of which the following is a specification, reference being had to the accompanying drawing, forming part thereof.

The figure is a perspective view of a heater cabinet, showing my new design.

I claim:

The ornamental design for a heater cabinet, substantially as shown.

EUGENE L. SNYDER.
